UNITED STATES PATENT OFFICE.

JOHN Q. CLARKE, OF CRAWFORDSVILLE, INDIANA.

SELF-SERVING HOG-TROUGH.

1,234,731.

Specification of Letters Patent.

Patented July 31, 1917.

Application filed August 19, 1916. Serial No. 115,830.

To all whom it may concern:

Be it known that I, JOHN Q. CLARKE, a citizen of the United States, residing at Crawfordsville, in the county of Montgomery and State of Indiana, have invented certain new and useful Improvements in Self-Serving Hog-Troughs; and I do hereby declare the following to be a full, clear, and exact description of the invention, such as will enable others skilled in the art to which it appertains to make and use the same.

This invention relates to self-serving or feeding hog troughs.

The object of this invention is the provision of a trough, which trough is divided by partitions struck up from the medial portions thereof separating the trough into separate chambers. The troughs are secured and held firmly together by a hopper 20 supporting frame, and the hopper supporting frame is constructed of angle iron and has the hopper supported therein above the trough, and a plurality of agitators supported upon the V-shaped partition of the 25 trough and extending up into the hopper.

A still further object of this invention is to provide a plurality of troughs formed from a single sheet of metal and this metal having struck up centrally therein a V-shaped partition which divides the trough into separate chambers, and the V-shaped partition is adapted to have positioned thereon agitators, the ends of which are directed downwardly into the troughs and 35 may be operated by the animals when feeding forcing the feed into the hopper at all times.

A still further object of this invention is the provision of a deflecting member which 40 is so secured to the opposite sides of the hopper and extend downwardly and outwardly beyond the forward edges of the trough so as to prevent rain or other water from running down into the troughs or 45 upon the backs of the animals while the same are eating.

A still further object of this invention is the provision of a pair of troughs formed of a single sheet of metal and supported 50 by a suitable hopper supporting frame and which is so constructed as to prevent the

hogs from crowding one another while eating and also prevent them from climbing into the trough while eating and thus spilling the food from the troughs by their feet.

55

A further object of this invention is the provision of a trough of this character which will be simple, practical and comparatively inexpensive, which can be manufactured and sold at a comparatively small 60 cost.

With these and other objects in view the invention consists in the novel combination, arrangement of parts hereinafter more fully described and pointed out in the claims 65 hereto appended.

In the drawings—

Figure 1 is a perspective view of my self-serving hog trough made in accordance with this invention,

70

Fig. 2 is a vertical sectional view of the same,

Fig. 3 is a longitudinal sectional view, and

Fig. 4 is a perspective view of one of the 75 agitators.

Like numerals of reference designate corresponding parts in all the figures of the drawings.

Referring more particularly to the drawings, the numeral 1 designates a supporting frame in its entirety which comprises in its construction angle bars 2 and 3 which constitute the base members and having connected thereto at each end the supporting 85 legs 4 by suitable rivets 5. Connected to the upper ends of the legs are the curved bars 6 which bars are arranged in pairs and have their medial portions secured to the vertical flange of the angle bars 2 and 3 as at 90 7, and interposed between each pair of the curved bars 6 are the plates 8. The plates constitute the ends of the troughs 9 and 10 which will be hereinafter more fully described. The troughs 9 and 10 are formed 95 side by side out of one piece of sheet metal 11 having its medial portions struck up to define the inverted V-shaped partition 12 in cross section, which partition divides the trough into separate troughs 9 and 10 and 100 also acts as a deflector for the feed when the same passes into the trough from the

hopper. The upper outer edges of the troughs 9 and 10 are disposed below the plane of the apex of the inverted V-shaped partition, the purpose of which will be herein-
5 after more fully described.

The rectangular frame 13 is secured to the upper edges of the end plates 8 and the outer upper edges of the troughs 9 and 10. Secured at one end to the opposite corners 10 of the frame 13 are the uprights 14 rigidly secured to the corners of the frame 13 as at 15 and extend upwardly therefrom. The uprights 14 have secured thereto the end walls 15 and 16. The feed hopper 17 is mounted longitudinally and midway between the troughs. The hopper comprises end walls 18 and 19, and the inclined side walls 20 and 21, the lower edges of the side walls are provided with the outwardly directed horizontally disposed flanges 23 and the lower edges of the inclined side walls are disposed below the apex of the partition 12 and on opposite sides thereof forming the feed passages 24. Hingedly secured to 25 the upper edges of the hopper is a cover 25 which is provided with a hasp 26 which is adapted to fit over the staple 27 carried by the side wall 21 of the hopper for keeping the cover in a closed position.

30 Secured to the upper edges of the uprights 14 are the rain deflectors 28, which are arranged to be secured to the side walls of the hopper and inclined downwardly therefrom, have their lower outer edges bent upwardly as at 29 to deflect the rain and prevent the water from flowing into the troughs or upon the backs of the animals while feeding. Secured to the under side of the deflectors as at 30 are the braces 31 which are secured at 35 one end to the underside of the deflectors and at their opposite ends to the side walls of the hopper, thus reinforcing the hopper and holding the deflectors in position. Reinforcing bars 32 are secured to the side 40 walls of the hopper and have their lower ends connected to the rectangular frame 13 as at 33 for reinforcing and holding the hopper in an upright position. Arranged transversely across the hopper centrally 45 thereof is the strap 34 which has its opposite ends connected to the side rails of the frame 13 as at 35 and has its medial portion provided with an inverted V-shaped member 36 which is adapted to rest upon the inverted 50 V-shaped partition of the troughs.

55 The agitators designated 37 as an entirety comprise the U-shaped bars 38 having the extreme ends of their legs bent upwardly as at 39 and are provided with openings 40. 60 The horizontal bar 41 is secured between the eyes of the legs of the U-shaped members 38 by the bolts 41^a and nuts 42. Secured to the horizontal bar at one end are the agitators 43 which extend vertically

from the bar 41 and are in spaced relation 65 thereon. It can be readily seen that when the agitators are assembled that by connecting the eyes 40 of the members 38 to the bar 41 there is provided an inverted V-shaped portion 45 which is adapted to fit over the 70 inverted V-shaped partition which divides the trough into two troughs 9 and 10. The web portions 46 of the agitators extend into the opposite troughs 9 and 10 and are adapted to be moved downwardly by the contact 75 with the nose of the animal when feeding thereby oscillating the arms 43 which will cause the feed to fall down into the trough and the troughs become filled with food at all times.

80 After the agitators are placed upon the V-shaped partitions it will be understood that the relative longitudinal movement of the agitators will be limited by contact with the strap which is arranged centrally across 85 the partition. The strap also serves to hold the agitators at a spaced distance apart.

It will be readily seen that when assembling the device and the agitators are positioned in place and the feed is in the 90 hopper, when the hogs are feeding their noses will come in contact with the webs of the agitators thereby oscillating the bars 43 which will move the feed downwardly into the hopper. It is also to be understood that 95 should the trough be out in the open weather, the rain falling would hit the deflectors 28 and would be carried off at the opposite ends thereby preventing the water from mixing with the corn or other food 100 in the troughs or running off on the backs of the hogs while eating. It is also understood that these deflectors will serve to prevent the hogs from getting their feet into the troughs and thus pulling the feed therefrom.

105 What is claimed is:—

1. An animal trough of the class described including a supporting frame having end walls, a hopper rigidly mounted in the 110 frame and secured to the end walls, troughs positioned in the frame and located in the hopper, said troughs divided by an inverted V-shaped partition, reinforcing straps extending centrally across the partition and 115 connected to the peripheral edges of the troughs, an agitator supported upon the apex of the V-shaped partition and located in the trough on opposite sides of the partition, said straps limiting the longitudinal 120 movement of the agitators toward one another.

2. A feed trough of the character described including a supporting frame having end walls, a hopper rigidly secured to 125 the end walls and descending in the frame, a trough formed of a single sheet of metal connected to the frame and positioned below

the hopper, said trough having its medial portion struck up to provide an inverted V-shaped partition, and agitators supported upon the partition and extending in each of the troughs, means extending upwardly from the agitators into the hopper for urging the contents of the hopper into the troughs, and straps extending transversely across the troughs and apex of the inverted

V-shaped partition for rigidly holding the troughs against separation.

In testimony whereof I affix my signature in presence of two witnesses.

JOHN Q. CLARKE.
